UNITED STATES PATENT OFFICE.

MARCELLUS B. FUQUA, OF MCKINNEY, TEXAS.

SEWING-MACHINE.

SPECIFICATION forming part of Letters Patent No. 244,881, dated July 26, 1881.

Application filed April 2, 1881. (No model.)

To all whom it may concern:

Be it known that I, MARCELLUS B. FUQUA, a citizen of the United States, resident at McKinney, in the county of Collin and State of Texas, have invented certain new and useful Improvements in Sewing-Machines; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

Figure 1 is a perspective view of the needle in place, and Figs. 2 and 3 are detail views of the clamp.

This invention relates to improvements in devices for adjusting sewing-machine needles.

The invention consists in the construction hereinafter set forth.

In the annexed drawings, A is the needle-bar, preferably notched at *a* at its lower end. B is a clamp, having the ears *b b'*, the former having the threaded perforation *a'* to receive the clamp-screw C. The latter, *b'*, has the inside groove, *c*, top groove, *d*, and outside groove, *e*.

E is the needle, having its upper end, *f*, turned at right angles and provided with the eye *g*, the needles for each kind of machine to be of one specific length, so that when ad-

justed, as hereinafter described, they will be ready for work.

The needle E is placed in the clamp with the upper part of its stem *h* resting in the groove *c* and its upper end, *f*, in groove *d*. The clamp is then put about the end of the needle-bar, with the ear *b'*, carrying the needle, resting in the notch *a*. The screw C is tightened, the bar preferably having a hole to receive it, and the height of the needle can readily be adjusted by resting the turned-out part *f* in groove *d* before finally tightening the screw C. Through eye *g* the thread is guided and along groove *e* to the needle-eye. 45

I am aware that a needle having a bent upper end is not new, and that a clamp is also not new; but, as far as I am aware, they have not been used together, and such conjuncture demands a special construction and adaptation. 50 Therefore

What I claim is—

The clamp B, having arms *b b'*, the latter provided with grooves *d* and *e*, in combination with the needle E, having its upper end bent 55 at *h* and *g*, and the screw C, as set forth.

In testimony whereof I affix my signature in presence of two witnesses.

MARCELLUS B. FUQUA.
